(57) **CLAIM**

The ornamental design for an outer portion of a multipiece wheel, as shown and described.

DESCRIPTION

FIG. 1 is a perspective view of an outer portion of a multipiece wheel according to the design.

FIG. 2 is a front view of FIG. 1.

FIG. 3 is a bottom view of FIG. 1; and,

FIG. 4 is a side view of FIG. 1.

The broken lines shown herein are for illustrative purposes only and form no part of the claimed design.

1 Claim, 3 Drawing Sheets

FIG. 1

FIG. 2

FIG. 3

FIG. 4
